UNITED STATES PATENT OFFICE

WILLIAM S. TOWNSEND, OF ROCHESTER, PENNSYLVANIA

DISPENSING DEVICE

Application filed December 2, 1929. Serial No. 410,895.

This invention pertains to liquid dispensing apparatus, and more particularly to liquid containers which are adapted to be self-supporting for the supply of the contents therefrom to an adjacent receptacle, such as the crankcase of an automobile.

At present, when lubricating oil is supplied to the crankcase of an automobile, it is necessary for the filling station attendant to remain at the engine and hold the lubricant receptacle during the entire period that the oil is flowing out of the receptacle and into the crankcase. This of course is a very tedious operation, especially during cold weather when oil flows very slowly, and when a large quantity of oil is being put into the engine, it makes it necessary for the attendant to remain at the engine for quite an appreciable period. A majority of the purchases of oil today are made by motorists who have the crankcase completely drained and then filled with fresh oil, the quantities supplied to the engine being from one to two gallons. The filling is a slow process, and the filling station attendant can do nothing else during the entire filling operation.

It is therefore an object of this invention to provide a device which may be associated with the engine and an oil receptacle, whereby the receptacle may be supported independent of the attendant adjacent the engine during the discharge from the receptacle.

Another object of the invention is to provide a dispensing device particularly adapted for filling crankcases of automobiles, which is of universal application for this or other dispensing operations.

A further object is to provide a dispensing device which may be used with any automobile for filling the crankcase thereof, one which is inexpensive to make and maintain, and fulfills all requirements of manufacture and service.

With these and various other objects in

view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a sectional elevation showing the device in supported filling relation to an engine block and the crankcase inlet thereof;

Figure 2 is a top plan view of the parts illustrated in Figure 1;

Figure 3 is a fragmentary elevation corresponding to Figure 1, showing a modified form of supporting device for the receptacle; and

Figure 4 is a fragmentary elevation of a modified form of actuating device for dispensing lubricant from the receptacle illustrated in Figure 1.

Referring first of all more particularly to the device as illustrated in Figures 1 and 2, it has been found that in substantially all automobiles there are a number of parts which are common; they are the tie rod 10 disposed between and connecting the radiator and cowl of the car, and the engine block 12, the engine block being provided with a suitable crankcase (not shown) having an oil filling opening 14 for supplying oil thereto.

The dispensing device includes a receptacle 16 having a handle 18 thereon for proper manipulation thereof, the receptacle being provided with a suitable depending skirt 20 forming a standard therefor, said skirt having an interrupted portion 22 through which the flexible hose 24 extends, said hose being provided with a nozzle 26 adapted to be inserted into an opening 14 for supplying lubricant thereto. The flexible hose 24 is in communication with a valve fitting, shown in the nature of an elbow 28, having a valve seat 30, the flow of liquid through said seat

being controlled by the valve 32. The valve 32 is secured to the lever 34, pivotally mounted as at 36 on the support or standard 38 provided in the receptacle, the end remote from the valve being pivoted as at 40 to the operating rod 42 extending upwardly through suitable guides 44 provided on the inside of the receptacle. The upper end of the rod 42 is threaded as at 46 and extends through a correspondingly threaded actuating nut 48 which is rotatably mounted in the bracket 50 fixed to the receptacle. The nut 48 is provided with spaced shoulders 52 embracing a portion of the member 50, and an upper thumb screw portion 54, which portion may be rotated for moving the valve 32 to opened or closed position through movement of the rod 42, the nut serving to lock the valve in any desired position as there is no relative movement of translation between the nut and the member 50.

The operating means for the valve may be varied somewhat, as illustrated in Figure 4, wherein the upper end of the rod 42 is downwardly notched with a plurality of notches 146, the notched portion of the rod extending through the member 50, said member being provided with an elongated slot 150 whereby the upper end of the rod 42 may be depressed to open the valve 32 the desired amount, whereupon the valve may be locked in selected open position by hooking the selected notch 146 under a portion of the member 50 adjacent the outer end of the slot 150.

The receptacle may be provided with a suitable hook member 56 into which the flexible hose 24 may be hooked when the receptacle is in operative position, the valve 32 being closed. The receptacle is provided with a vertically disposed supporting member shown as a strip of metal 58 having a plurality of upwardly extending slots 60 disposed therein at suitable intervals, extending the entire depth of the receptacle.

In order then to support the receptacle in operative position wherein it is possible to open the valve 32 to dispense liquid from the receptacle through the hose 24, nozzle 26 say into opening 14, a bracket device 62 is provided, said bracket is provided with an upper hook portion 64 adapted to engage the tie rod 10, the bracket 62 being deflected as at 66 to provide a downwardly extending portion 68 to engage a portion of the engine block 12, said portion 68 being provided with spaced apertures along the length thereof. The member 62 is provided with a pedestal member or bracket 70 pivoted as at 72 to the brace member 74 which is provided with an enlarged end portion 76 having spaced headed pins 78 thereon adapted to be engaged in selected slots 60 in the member 58. The brace member 74 is provided with a brace member 80 pivoted thereto as at 82, the end of said brace member being reduced to the proper

sized portion 84 for engagement in selected slotted apertures in the member 68 whereby a triangular brace member is formed supported at a plurality of points, namely, on the tie rod and engine block, for supporting the receptacle 16, it being understood that the slots 60 may be provided with an upwardly extending enlarged portion 86 whereby the brace member 74 is locked in supporting position to the receptacle by the weight of said receptacle.

The brace member 62 may be varied somewhat, as shown in Figure 3 at 162, the brace member being provided with the hook portion 164 for engaging the tie rod 10, said brace member being supported at another point on the engine block 12. The brace member 162 is provided with a pedestal 170 pivoted at 172 to the brace member 174, which member is provided with an enlarged head portion 176 having headed pins 178 for engaging in slots 60 of the member 58 provided on the receptacle 16. The member 174 is notched as at 188 for the selected reception of the headed pins 190 and 192 provided on the offset head portion 194 of the brace member 180, said member being pivoted as at 196 to the pedestal 198 provided on the brace member 162.

When either of the brackets are not in use, they may be folded so that they are readily portable, and with the construction shown, it will be seen that the receptacle has only to be supported by the bracket structure in operative position and the valve opened, after which the attendant may go about other duties, such as tending other automobiles or attending to the gas, water or tires of the machine which is being supplied with lubricant.

It is, of course, to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In combination with a liquid container or the like having a support adjacent thereto, a liquid receptacle having means for selectively supplying liquid to said container or the like, means cooperating with said support and said receptacle for sustaining said receptacle in position to supply liquid to said container or the like, said last named means including a member adapted to releasably engage said support, and a pair of members cooperating with said receptacle and said first named member.

2. In a device of the character described, the combination of a lubricant container having a discharge hose, means in said container for controlling flow of lubricant through said hose, a slotted support disposed

on said container, a bracekt for supporting said container adjacent the fill opening of a vehicle whereby said hose can be received in said fill opening, said bracket having means received in said slots.

3. In a device of the character described, the combination of a lubricant container having a discharge hose, means in said container for controlling flow of lubricant through said hose, a slotted suppport disposed on said container, a bracket for supporting said container adjacent the fill opening of a vehicle whereby said hose can be received in said fill opening, said bracket including a plurality of members, one of said members having means received in said slots, another of said members forming supporting means for said first-named member, and a third member forming a strut for said other members.

20 4. In a device of the character described, the combination of a lubricant container having a discharge hose, means in said container for controlling flow of lubricant through said hose, a bracket for supporting said container adjacent the fill opening of a vehicle whereby said hose can be received in said fill opening, said bracket including a support engaging member having securing means thereon, and a pair of members each engaging a portion of the support engaging member and each other, and being adapted to be disposed in angular position with respect to each other, one of said members having means thereon for attachment to said container to hold said container adjacent said fill opening.

5. In a device of the character described, the combination of a lubricant container having a discharge hose, means in said container for controlling flow of lubricant through said hose, a bracket for supporting said container adjacent the fill opening of a vehicle whereby said hose can be received in said fill opening, said bracket including a support engaging member having securing means thereon, and a pair of members each engaging a portion of the support engaging member and each other, and being adapted to be disposed in angular position with respect to each other, one of said second-named members having means thereon for attachment to said container to hold said container adjacent said fill opening.

6. In a device of the character described, the combination of a lubricant container having a discharge hose, means in said container for controlling flow of lubricant through said hose, a bracket for supporting said container adjacent the fill opening of a vehicle whereby said hose can be received in said fill opening, said bracket including a support engaging member having securing means thereon, and a pair of members each engaging a portion of the support engaging member and each other, and being adapted to be disposed in angular position with respect to each other,

one of said second-named members having means thereon for attachment to said container to hold said container adjacent said fill opening, the other of said second-named members serving as a strut between said support engaging member and the other of said members for maintaining a rigid supporting structure for said container.

Signed at Rochester, Pennsylvania, this 29th day of November, 1929.
